UNITED STATES PATENT OFFICE.

CHAS. PONTEZ AND C. L. McALPINE, OF NEW YORK, N. Y.

IMPROVEMENT IN FORMING SUB-FOUNDATIONS.

Specification forming part of Letters Patent No. 36,913, dated November 11, 1862; antedated May 11, 1862.

To all whom it may concern:

Be it known that we, CHARLES PONTEZ and CHARLES L. McALPINE, both of the city, county, and State of New York, have jointly invented a new and improved method of forming sub-foundations which serve as bases for sunken hollow cylinders or piles of other form; and we do hereby declare the following to be a full and exact description thereof, reference being had to the accompanying drawings, and to the letters of reference marked thereon.

Prior to our improvement hollow cylinders or piles of other form, intended for the support of bridges or other similar structures, when sunk by any of the known methods to any desired depth, have directly been filled with sand or concrete. This is done, mainly, with the intention to impart solidity and inertia to the hollow bodies.

In operating with our improvement we do not proceed to fill the hollow pile; but we form a foundation of concrete or other solid material, which extends laterally beyond and beneath the area inclosed by the hollow pile. Thus a permanent sub-foundation is formed having a larger bearing-surface than the original foundation hollow pile.

To enable others to use our invention, we will proceed to describe our mode of working.

When, for example, an iron cylinder six feet in diameter has been sunk through water, sand, clay, or other material to any desired depth, the men inside the cylinder, working in a condensed atmosphere, excavate under its lower edge laterally and downward for several feet, the distance and depth depending on the character of the soil and the auxiliary means used to prevent it from caving in. The space excavated is filled with concrete or other

suitable solid material. In this manner successive portions are excavated until an enlarged area is formed, which sustains the cylinder. The process may further be continued by drawing up the cylinder some distance, and in like manner laying successive courses of concrete masonry or other solid material until the concrete pile has been built up to the surface of the water. All the material used in the construction of the pile is carried down through the cylinder. A permanent foundation can in this manner be established, and a great saving effected in the cost of the cylinder.

In the accompanying drawings, Figure 1 is a longitudinal elevation showing a cylinder sunk through water, sand, clay, or other material and resting on a concrete sub-foundation. Fig. 2 is a transverse section of the cylinder at its base, with the concrete foundation laid in sections.

Letter A is the cylinder, and B the concrete foundation.

We do not claim the sinking hollow piles through sand, clay, or other material, nor the filling in of the same with concrete or other solid material; but

What we claim, and desire to secure by Letters Patent, is—

The method of forming sub-foundations, as herein shown and described, which consists substantially in extending the foundation from within the tube, as set forth.

CHARLES PONTEZ.
C. L. McALPINE.
